UNITED STATES PATENT OFFICE

SYLVANUS A. REED, OF NEW YORK, N. Y., ASSIGNOR TO REED PROPELLER CO. INC., OF GARDEN CITY, NEW YORK, A CORPORATION OF NEW YORK

AERONAUTICAL PROPELLER

Application filed August 6, 1929. Serial No. 383,921.

My invention relates to aeronautical propellers.

In a previously filed application, Serial #348,587, now Patent 1,778,340 issued Oct. 5 14, 1930, solid metal propeller blades having in one or both faces thereof weight reducing recesses not injuriously impairing the required structural strength of the blades are described and illustrated. Where such recesses are provided it is proposed to use non-structural surface restoring means or devices. In Fig. 3 of said patent there is illustrated a form of propeller having separate and detachable blades, which said 10 blades at their inner ends, are preferably substantially cylindrical and anchored, in any suitable manner, to and within the side branch ferrules of a propeller hub. Such a propeller is also illustrated in the drawings 15 of the present application.

As distinguished from said earlier filed application, the present invention contemplates improved means whereby this latter type or form of propeller blade may be reduced, or further reduced in weight, which means consists in boring a hole into the inner cylindrical end of the blade, leaving thereby a substantially cylindrical shell with walls sufficient in strength and thickness to sustain 20 safely the operative stresses of the propeller. Preferably said hole is extended into the blade a certain distance, and beyond its termination, if desired, the weight reducing 25 depressions or recesses and surface restoring means above referred to, may be provided. Where a heavy material such as steel 30 is utilized for propeller blades, such or any weight reduction consistent with retaining in the blade sufficient strength is of the utmost 35 importance.

In the drawings, wherein like reference characters denote like or corresponding parts,

Fig. 1 is a plan view of a detachable blade 40 metal aeronautical propeller embodying my invention, the propeller blades having formed therein lightening recesses, and the recesses of one blade being shown uncovered;

Fig. 2 is an enlarged view, somewhat similar to Fig. 1, showing in dotted lines the

weight reducing holes formed in the inner blade ends as well as the weight reducing recesses and surface restoring means previously referred to;

Fig. 3 is a section on the line 3—3 of 55 Fig. 2, and

Fig. 4 is a section on the line 4—4 of Fig. 2.

In the embodiment of the invention selected for illustration, separate and detachable 60 blades 10—10 are shown as anchored at their inner ends in the side branch ferrules 11—11 of a metal hub 12. Said blades 10—10 are preferably solid throughout and each in its entirety is forged hot between steel dies, preferably from alloy steel, having high tensile strength, elasticity and fatigue limit, but may, if desired, be made of other forged or rolled metal alloys such, for instance, as strong alloys of aluminum or magnesium. The desired pitch angle of the blades may be obtained in any well known manner. Preferably said blades, at their inner ends, are anchored within the ferrules 11 as by interlocking shoulders and recesses 13—14 as shown 70 (see Fig. 4), or, if desired, the anchorages may be so formed and constructed as to admit of blade adjustment both axially and rotatably. Such anchorage and/or adjustments, however, form no part of the present invention. 75

Within the inner end of the stem portion of each blade 10, a hole 15 is bored longitudinally of the blade axis, which said hole, throughout a portion of its depth, may be reduced in diameter as indicated at 16. The blades 10, at their inner ends, being substantially cylindrical in cross-section, the holes 15—16 are preferably similarly formed and of such size and depth as to provide for a maximum of weight reduction consistent with leaving in the walls of the blade stems or inner end portions that strength and bulk of material necessary to sustain safely the stresses of service operation. Or, if desired, the holes 15—16 may be extended for a certain distance along the axes of the blades, and beyond the termination of the holes, the weight reducing depressions or recesses 17 and the surface restoring means or devices 18 80 85 90 95 100

disclosed in my said earlier filed application, may be utilized. Whether the holes 15—16 are used alone or in combination with the lightening recesses, an exceptionally light though strong solid metal propeller blade is obtained.

The most efficient diameter and length for the bores vary with different metals and different grades of the same metal. However, when my invention is applied to a propeller, preferably (as shown in Figs. 2 and 4) the diameter of the larger bore approximates 75% of the diameter of the cylindrical inner end portion and the outer end of the longer bore extends to a point approximating 1/6th of the blade length from the axis of the propeller, but I do not confine myself to any given size or depth of hole, nor to any special means of restoring the blade surfaces where lightening depressions or recesses are provided. In boring the holes into the blade stems, from the inner blade ends along the longitudinal axes of the blades, only that portion of each blade having an excess of bulk and material is affected. No deviation from the conventional exterior shape and size of the inner blade ends is required and it becomes unnecessary moreover, to provide a propeller hub of a different form than that now extensively used.

While I have described my invention in detail in its present preferred embodiment, it will be obvious to those skilled in the art after understanding my invention, that various changes and modifications may be made therein without departing from the spirit or scope thereof. I aim in the appended claims to cover all such modifications and changes.

What I claim is:

40 1. A propeller blade having a substantially cylindrical inner end portion adapted for anchorage to a propeller hub, said blade having formed within said inner end portion a longitudinally extending bore of such width and depth as to provide for maximum weight reduction consistent with retaining in the wall of the bore sufficient strength to sustain safely the stresses of service operation.

2. A propeller blade having a substantially cylindrical inner end portion adapted for anchorage to a propeller hub, said blade having its cylindrical inner end portion bored substantially along the longitudinal blade axis and said bore having a maximum of width and depth consistent with retaining in its defining wall sufficient strength and bulk of material to sustain safely the stresses of service operation.

3. A propeller blade having a substantially cylindrical inner end portion adapted for anchorage within a side branch ferrule of a propeller hub, said blade having its cylindrical inner end bored substantially along the longitudinal blade axis, and said bore extending radially out from said inner blade end and

having a maximum of width and depth consistent with retaining in the inner end portion of the blade sufficient bulk and strength of material to sustain safely the stresses of service operation.

4. A propeller blade having a substantially cylindrical inner end portion adapted for anchorage to a propeller hub, said blade having formed within said inner end portion a longitudinally extending bore of such width and depth as to provide for maximum weight reduction consistent with retaining in the wall of the bore sufficient strength to sustain safely the stresses of service operation, and said blade, beyond the termination of said blade lightening bore, having formed therein surface recesses for further weight reduction, and non-structural surface restoring means associated with said recesses.

5. In an aeronautical propeller, an integral and solid blade having formed within the inner two-thirds of the blade length a longitudinally extending bore, and also having formed beyond the termination of said longitudinally extending bore still within the inner two-thirds of the blade length, surface recesses for further weight reduction, and non-structural surface restoring means associated with said recesses.

6. In an aeronautical propeller, an integral blade having a substantially cylindrical inner portion and having formed within said inner portion a weight reducing longitudinally extending bore, said bore being confined to the inner two-thirds of the blade length.

7. In an aeronautical propeller, a propeller hub, an integral and solid blade having a substantially cylindrical inner end portion adapted for anchorage to said propeller hub, said blade having formed within said inner end portion a longitudinally extending bore and having formed beyond said first named bore a second longitudinally extending bore of substantially smaller diameter than the first mentioned bore.

8. In an aeronautical propeller, an integral and solid blade having a substantially cylindrical inner end portion and having formed within said inner end portion a longitudinally extending bore, the diameter of said bore being less than 80% and more than 50% of the diameter of said cylindrical inner end portion.

9. In an aeronautical propeller, an integral and solid blade having a substantially cylindrical inner end portion and having formed within said inner end portion a longitudinally extending bore, the diameter of said bore being less than 80% of the diameter of said cylindrical inner end portion.

10. In an aeronautical propeller, an integral and solid blade having a substantially cylindrical inner end portion and having formed within said inner end portion a lon-

gitudinally extending bore, the diameter of said bore being approximately 75% of the diameter of the cylindrical inner end portion.

- 5 11. A propeller blade having a substantially cylindrical inner end portion adapted for anchorage within a side branch ferrule of a propeller hub, said blade having a longitudinally extending bore beginning at its
10 inner end and terminating at a point within said ferrule, whereby the weight of the blade is lessened without affecting its strength.

12. A propeller blade having a substantially cylindrical inner end portion adapted
15 for anchorage within a side branch ferrule of a propeller hub, said blade having a longitudinally extending bore beginning at its inner end and terminating at a point within said ferrule, a second bore extending longitudinally from the outer end of said first named bore and of less diameter than the first named bore, whereby the weight of the blade is lessened without affecting its strength.

- 25 In testimony whereof I hereunto affix my signature.
